UNITED STATES PATENT OFFICE

OTTO H. HEINE, OF EUGENE, OREGON

THATCHED STOCK SHELTER

Application filed May 9, 1928. Serial No. 276,483.

This invention relates to the housing of stock and provides a shelter which utilizes straw for covering the roof and sides, the same being supported by a framework over 5 which the straw is thatched.

The material comprising the framework is prepared at the mill and shipped to the place ready to be set up and covered.

The invention contemplates a structure including posts, rafters and stringers over which the covering of straw is arranged to form a thatch.

While the drawings illustrate a preferred embodiment of the invention it is to be understood that in adapting the means to meet specific needs and requirements the design may be varied and changes in the minor details of construction may be resorted to within the scope of the invention as claimed, 20 without departing from the spirit thereof.

For a full understanding of the invention and the merits thereof, reference is to be had to the following description and the drawings hereto attached, in which,—

25 Figure 1 is an end view of a stock shelter, or shed, embodying the invention.

Figure 2 is a longitudinal sectional view of the frame.

Figure 3 is a top plan view of the framing, 30 the covering being omitted.

Figure 4 is a horizontal sectional view of an end portion of the framing on the line 4—4 of Figure 1.

Figure 5 is an enlarged detail perspective 35 view of the meeting ends of a post and rafter.

Corresponding and like parts are referred to in the following description and designated in the several views of the drawing by like reference characters.

40 In the drawings, wherein for the purpose of illustration is shown a preferred embodiment of the invention, the numeral 1 denotes a plurality of posts, 2 rafters, and 3 stringers, the posts and rafters preferably embodying a composite structure and comprising

45 timbers arranged side by side and spiked or otherwise secured. The posts 1 are set into a footing of concrete let into openings formed in the ground. This footing is designated

50 by the numeral 4 and is tamped into an open-

ing formed in the ground. The lower ends of the posts 1 are treated for protection against the ravages of insects and moisture. As indicated most clearly in Figure 5 of the drawings, the posts are formed of three timbers 55 which are arranged to provide a mortise 5 at the upper end to receive a tongue 6 at the bottom side of the rafters. The posts 1 are arranged in longitudinal and transverse lines and are connected at their upper ends by the rafters 2 and stringers 3, the latter forming longitudinal ties and the rafters transverse ties. The rafters are likewise formed of three timbers arranged side by side and spiked, or otherwise secured. 60

The middle timber is arranged so that its lower marginal portion projects below the adjacent edges of the side timbers to form the tongue 6 which enters the mortises 5 at the upper ends of the transversely alining 65 posts. The stringers 3 are closely related to form supporting means for the thatch 7, which usually consists of straw. An opening 8 is provided at each end of the structure 70 for the ingress and egress of the stock. The portions at the sides of the opening 8 are closed by boards 9 and windows 10. The lower portion of the sides is closed by boards 11, the upper portion being open. The roof and sides of the structure are enclosed by a 75 thatch 7 which preferably consists of straw, the thatching being effected preferably by means of a pneumatic stacker. The thatch or covering may be of any depth depending upon the available amount of material. 80 Spaces 12 are formed between the sides of the structure and the sides of the thatch and these spaces are utilized for receiving feed which may be placed in mangers, not shown, 85 or supplied in any determinate way for the stock to feed upon as required.

The invention provides a shelter for stock involving a minimum cost for material and labor since it may be readily set up and utilizes material which is usually stacked, 90 and which when stacked, is utilized as protective means for housing stock.

Having thus described the invention, I claim:

1. A stock shelter including a supporting 100

structure having the lower portion of its walls enclosed and the upper portion open, an end wall being provided with an entrance for stock and a thatch of straw covering the 5 top and sides of the structure, and having the side portions spaced from the side walls of the structure whereby provision is had for the placing of feed for the stock.

2. A shelter for stock comprising a supporting structure including posts, rafters and stringers, and a thatch of straw covering the roof of the structure and extending downwardly along the sides thereof from which it is spaced to provide for the placing of feed, an end of the shelter being provided with an entrance for stock.

3. A stock shelter comprising longitudinal and transverse lines of posts, rafters connecting the transverse lines of posts, stringers connecting the rafters, boards enclosing the lower portion of the sides and ends of the structure leaving end openings for ingress and egress of the stock, windows closing the upper portion of the end walls at the 25 sides of the openings, and a thatch of straw covering the roof and sides of the structure and having the depending side portions spaced from the side walls of the structure to provide spaces for the reception of feed.

30 In testimony whereof I affix my signature.
OTTO H. HEINE. [L.S.]
